CLAIM

The ornamental design for a liquid container, as shown and described.

DESCRIPTION

FIG. 1 is a front perspective view of a liquid container in accordance with the present invention.

FIG. 2 is a rear perspective view thereof.

FIG. 3 is a front view thereof.

FIG. 4 is a right view thereof.

FIG. 5 is a left view thereof.

FIG. 6 is a top view thereof.

FIG. 7 is a bottom view thereof; and,

FIG. 8 is a rear view thereof.
